W. C. ADAMS

KNITTING MACHINE

Filed Feb. 7, 1923

INVENTOR:
William C. Adams,
by his attorney,
Charles S. Gooding.

UNITED STATES PATENT OFFICE.

WILLIAM C. ADAMS, OF ATTLEBORO, MASSACHUSETTS.

KNITTING MACHINE.

Application filed February 7, 1923. Serial No. 617,483.

To all whom it may concern:

Be it known that I, WILLIAM C. ADAMS, a citizen of the United States, residing at Attleboro, in the county of Bristol and State 5 of Massachusetts, have invented new and useful Improvements in Knitting Machines, of which the following is a specification.

This invention relates to an improved knitting machine.

10 The object of the invention is to provide a knitting machine which can be operated by hand to produce a tubular knitted fabric, the same being particularly adapted for use by children to accurately knit a tubular fabric in a neat, expeditious and workman-like manner.

The invention consists primarily in a knitting machine embodying a needle carrier with a series of knitting needles slidably 20 mounted thereon, which is slidably and rotatably mounted in a holder, and means for imparting a reciprocatory movement to the needles relatively to the needle carrier.

The invention further consists in the combination and arrangement of parts set forth in the following specification and particularly pointed out in the claims.

Referring to the drawings:

Figure 1 is a front elevation of my improved knitting machine.

Fig. 2 is a side elevation partly broken away and shown in section as viewed from the right of Fig. 1, showing the needle carrier moved upwardly from the position in 35 which it is illustrated in Fig. 1.

Fig. 3 is a plan view of the knitting machine.

Fig. 4 is a side elevation similar to Fig. 1 illustrating one step in threading up the 40 machine when the knitting operation is first started.

Fig. 5 is a plan view illustrating still further the manner in which the machine is threaded up preparatory to knitting the tube.

Like numerals refer to like parts throughout the several views of the drawings.

In the drawings, 5 is the needle carrier, which in this embodiment of my invention 50 consists of a cylindrical member, preferably of wood, which extends entirely through a holder 6 and projects to a substantial distance below said holder to form a handle 7 by means of which the needle carrier 5 may 55 be rotated and reciprocated upon the holder 6. The needle carrier is provided with a

plurality of slots 8, in this case four in number, which extend longitudinally thereof and form guideways in which are slidably mounted a plurality of latch needles 9. 60 Each of the latch needles is provided with a butt 10 extending laterally thereof and beyond the periphery of the needle carrier 5, and above the upper end of the holder a metal band 11 encircles the carrier 5 and is 65 fast thereto. This band serves to confine the needles in the slots 8 and further forms a stop to prevent the needles from moving beyond a certain distance in one direction relatively to the needle carrier. The needles are 70 prevented from moving beyond a certain distance downwardly or relatively to the holder 6 by the butts 10 thereof engaging the upper end of the needle holder.

The needle carrier 5 is provided with an 75 annular groove 12 in which is located an elastic band 13 which helps to position the needles in the grooves and supplies a friction to prevent the needles moving in their respective grooves, except when caused to do 80 so by positive means such as the engagement of the butts by the annular band 11, or by the upper end of the holder 6.

A bracket 14 is fastened to the holder 6 and has a laterally extending arm 15 at its 85 upper end which projects over the upper end of the holder and is adapted to be engaged successively by the butts of the needles 9 during the operation of the machine, whereby if an upward movement is given to 90 the carrier, one of the needles will be held against movement therewith and thus will be caused a reciprocatory movement of the carrier relatively to the needle.

The latch needles 9 are of the usual well-known construction and the carrier is made tubular to allow the knitted tube 16 to feed 95 downwardly therethrough.

The yarn 17 is fed to the machine from a ball or from a bobbin, as may be desired, 100 (not shown in the drawings) and passes through a tension device 18 formed by a screw eye which may be turned at different angles to increase or diminish the tension on the yarn. From the tension device 18 the 105 yarn passes upwardly and through the upper end of a yarn guide 19 consisting of a flat strip with an eye 20 at its upper end. This yarn guide is fastened rigidly to the holder 6.

110 During the operation of the device the carrier is guided by a lateral projection 26

which is held in engagement with the lower end of the holder 6 and is moved at intervals into slots 27 provided in and opening out of the lower end of the holder 6 by the operator.

In order to enable a needle to be easily removed from the needle carrier 5 the holder 6 is bevelled on an outer face 6' thereof from a point immediately adjacent the bore of the holder and the needle carrier which slides in said bore. It will be seen that by this construction if a latch becomes broken or if the needle becomes bent or if for any reason it is desired to remove the needle from the carrier and to insert a new needle in its place, that the carrier may be moved upwardly to the extent of its upward movement, that is, until the projection 26 arrives at the upper end of one of the slots, such as 27, and then the needle can be removed by grasping it by the butt and moving the butt outwardly and downwardly out of the carrier. The needle can also be inserted in the carrier in the same way and this construction enables the operator to easily replace the needles without taking the carrier out of the holder.

The general operation of the mechanism hereinbefore specifically described is as follows:—Assuming the different parts of the machine to be in the relative positions illustrated in Fig. 4, the yarn is passed upwardly through the tension device 18 and through the eye 20, the free end of the yarn being attached to the eye 31 of a weight 30 which is similar in construction to an ordinary fish line sinker, and this weight, together with the yarn 17, is then dropped down through the bore 32 of the needle carrier. The yarn should extend at least six inches below the end of the carrier at this stage of the threading operation. The carrier is held in the right hand and at the same time the holder is held at its extreme top. This will insure that all the needles are up while starting to thread the yarn into them. The next step in the threading operation is to take the yarn as it comes from the guide 19 and thread it in the needles as illustrated in Fig. 5 by winding it around the needles as shown. First it is passed from the back of the needle 33 around the same in a counterclockwise direction, thence to the needle 21 and around that needle in a counterclockwise direction, then to the needle 23 and around that needle in a counterclockwise direction and then around the needle 24 in a counterclockwise direction drawing the yarn through the guide hole 20 in order to provide sufficient yarn to perform this threading operation.

The next step in the threading operation is to pull down on the end of the yarn which has been passed through the carrier until the loops on the needles are all drawn down against the top of the carrier. At this time

care must be taken that all the needle latches are down. Now turn the carrier until the needle 33 is at the front or under the arm 15. Be sure that the yarn from the guide is in the hook of needle 33 and that the yarn from the guide to the tension is taut. The needles now being threaded with the yarn, and assuming the parts to be in the relative positions illustrated in Fig. 1 with the yarn extending from the needle 21 across the needle 22 outside its latch 23 and across the needle 24 beneath the hook 25 thereof suitable tension is given to the yarn 17 by the tension device 18. Tension is also imparted to the yarn which extends down through the carrier by allowing it to pass between two fingers of the hand of the operator which at this time grasps the handle portion 7 of the carrier. The knitting operation is then performed as follows:—The holder 6 is supported by the other hand of the operator. The operator now pushes the carrier upwardly while holding the holder 6 stationary and the projection 26 enters one of the slots, 27, and passes upwardly therein until it arrives at the upper end of the slot, this end of the slot being closed constitutes a stop to limit the upward movement of the carrier relatively to the holder by reason of the projection 26 abutting against the upper end thereof.

It will be evident that during this movement, the butt of the needle 22 will engage the underside of the arm 15 on the bracket 14 and said needle will therefore be held stationary while the carrier is moving upwardly, thus the needle 22 will at this time be caused to form a loop in the yarn 17 and this loop of yarn will be drawn through the previous loop which hangs upon said needle 22 thus forming the knitting stitch.

The next motion of the operator is to move the carrier downwardly until the projection 26 passes out of the slot 27. At this time the needle 22 will occupy the position relatively to the carrier shown in Fig. 1.

The next step in the operation is performed by the operator rotating the carrier in the direction of the arrow *a*, Fig. 1, a quarter turn, whereupon the butt of the needle 22 will pass out from under the stop arm 15 and the butt of the needle 24 will pass under said stop. The projection 26 is now in alignment with another of the slots 27, namely, the slot 28, Fig. 1, and the operation is again repeated.

During the knitting operation hereinbefore described, when the needle carrier is moved upwardly all of the needles move with it except the needle the butt of which is beneath the stop 15, and these needles are held in frictional engagement with the carrier by the elastic band 13, so that they travel with it during its upward movement.

During the downward movement of the

carrier, the needles travel with the carrier with the exception of the needle whose butt is in engagement with the stop arm 15 and are carried positively downward against the 5 upper end of the holder 6 by the band 11 fast to the carrier 5, as illustrated in Fig. 1.

After each loop has been formed and drawn through the preceding loop, the quarter rotation is given to the needle carrier, as 10 hereinbefore described, and then the reciprocatory movement is imparted thereto. Thus it will be seen that by alternately imparting to the needle carrier a reciprocatory and rotary movement, the tubular knitted 15 fabric 16 will be knitted.

I claim:—

1. A knitting machine having, in combination, a needle carrier, a series of knitting needles slidably mounted thereon, a holder 20 in which said carrier is rotatably and slidably mounted and means to guide said carrier while an alternate rotating and slidable motion is being imparted thereto.

2. A knitting machine having, in combination, a needle carrier, a series of knitting needles slidably mounted thereon, a holder in which said carrier is rotatably and slidably mounted and a stop on said holder adapted to be successively engaged by said 30 needles to hold them stationary relatively to said holder when a reciprocatory movement is imparted to said carrier.

3. A knitting machine having, in combination, a cylindrical needle carrier, a 35 series of knitting needles slidably mounted thereon, a holder in which said carrier is rotatably and slidably mounted, said cylindrical needle carrier extending entirely through and below said holder, a lateral projection on said carrier positioned to engage the lower end of said holder, a plurality of slots being provided in said holder and opening out of the bottom thereof to receive said projection, whereby said carrier may be guided while an alternate rotating and sliding motion is being imparted thereto.

4. A knitting machine having, in combination, a cylindrical needle carrier, a series of knitting needles slidably mounted 50 thereon, a holder in which said carrier is rotatably and slidably mounted, said cylindrical needle carrier extending entirely through and below said holder, a lateral projection on said carrier positioned to engage the lower end of said holder, a plurality of slots being provided in said holder and opening out of the bottom thereof, whereby said carrier may be guided while an alternate rotating and sliding motion is being imparted thereto and means on said holder adapted to be successively engaged by said needles to hold them stationary relatively to said holder when a reciprocatory movement is imparted to said carrier.

5. A knitting machine having, in combi-

nation, a cylindrical needle carrier, a series of knitting needles slidably mounted thereon, a holder in which said carrier is rotatably and slidably mounted, said cylindrical needle carrier extending entirely through and below said holder, a lateral projection on said carrier positioned to engage the lower end of said holder, a plurality of slots being provided in said holder and opening out of the bottom thereof, whereby said carrier may be guided while an alternate rotating and sliding motion is being imparted thereto and a bracket fast to said holder and adapted to be successively engaged by the butts of said needles to hold them stationary relatively to said holder when a reciprocatory movement is imparted to said carrier.

6. A knitting machine having, in combination, a cylindrical needle carrier, a series of knitting needles slidably mounted thereon, a holder in which said carrier is rotatably and slidably mounted, said cylindrical needle carrier extending entirely through and below said holder, a lateral projection on said carrier positioned to engage the lower end of said holder, a plurality of slots being provided in said holder closed at the upper end thereof and opening out of the bottom of said holder to receive said projection whereby said carrier may be guided while an alternate rotating and sliding motion is being imparted thereto.

7. A knitting machine having, in combination, a needle carrier, a series of knitting needles slidably mounted thereon, a holder in which said carrier is rotatably and slidably mounted and a stop on said holder adapted to be successively engaged by the butts of said needles to hold them stationary relatively to said holder when a reciprocatory movement is imparted to said carrier while allowing said carrier to be rotated at the termination of each reciprocatory movement.

8. A knitting machine having, in combination, a needle carrier, a series of knitting needles slidably mounted thereon, each of said needles having a butt extending laterally from the shank thereof and projecting beyond the periphery of said carrier, a band encircling said carrier above said needle butts, means to hold said needles in frictional engagement with said carrier and a stop on said holder adapted to be successively engaged by said needles to hold them stationary relatively to said holder when an upward reciprocatory movement is imparted to said carrier, said needle butts being adapted to engage the upper end of said holder during the downward movement of said carrier, whereby said needles may be reciprocated relatively thereto.

9. A knitting machine having, in combination, a cylindrical needle carrier, a series

of knitting needles slidably mounted thereon, a holder in which said carrier is rotatably and slidably mounted, said cylindrical needle carrier extending entirely through 5 and below said holder, the lower end of said carrier constituting a handle whereby it may be manipulated and means to guide said carrier while an alternate rotating and sliding motion is being imparted there- 10 to.

10. A knitting machine having, in combination, a needle carrier, a series of knitting needles slidably mounted thereon, a holder in which said carrier is slidably and rotatably mounted, means to guide said carrier while an alternate rotary and slidable motion is being imparted thereto and a yarn guide 15 stationary relatively to said holder, whereby yarn may be guided to said needles.

11. A knitting machine having, in combination, a needle carrier, a series of knitting needles slidably mounted thereon, a holder in which said carrier is slidably and rotatably mounted, means to guide said carrier 20

while an alternate rotary and slidable motion is imparted thereto, a yarn guide stationary relatively to said holder, whereby yarn may be guided to said needles and a tension device stationary relatively to said holder, whereby yarn may be fed to said 25 needles under tension.

12. A knitting machine having, in combination, a needle carrier, a series of knitting needles slidably mounted thereon, a carrier holder in which said carrier is rotatably and 30 slidably mounted and means to guide said carrier while an alternate rotary and slid- able motion is being imparted thereto, an outer face of said carrier holder being bevelled from a point adjacent the carrier 35 outwardly and downwardly therefrom.

In testimony whereof I have hereunto set my hand in presence of two subscribing witnesses.

WILLIAM C. ADAMS.
